DESIGN FOR A HELICOPTER

Frank N. Piasecki, Lansdowne, Pa., assignor to
The Piasecki Helicopter Corporation, Morton,
Pa.

Application January 8, 1948, Serial No. 143,603

Term of patent 14 years

(Cl. D71—1)

To all whom it may concern:

Be it known that I, Frank N. Piasecki, a citizen of the United States of America, residing at Lansdowne, in the county of Delaware and State of Pennsylvania, have invented a certain new, original, and ornamental Design for Helicopter, of which the following is a specification, reference being had to the accompanying drawing, forming part thereof.

Figure 1 is a front elevational view of my new design for a helicopter.

Figure 2 is a top plan view of the same.

Figure 3 is a side elevational view of the same.

Figure 4 is a perspective view taken from the front of the machine.

Figure 5 is a perspective view taken from the rear of the machine.

The characteristic features of my design reside in the portions shown in full lines.

I claim:

The ornamental design for a helicopter, as shown and described.

FRANK N. PIASECKI.
